RECIPROCABLE SLIDE SWITCH FOR
APPLIANCES

Matthew G. Andis, Racine, Wis., assignor to Andis Clipper Co., Racine, Wis., a corporation of Wisconsin
Filed Feb. 1, 1962, Ser. No. 170,325
7 Claims. (Cl. 200—16)

This invention relates to an appliance switch.

The invention is exemplified in a switch for an electric hair clipper. The appliance casing provides a guideway along which a handle slide of dielectric material is reciprocable. Within the casing the slide is provided with a stud for propelling a floating contactor strip engaged intermediate its ends by the stud. A pocket formed within the dielectric material of the casing, and in the path of reciprocation of the contactor, contains a ball or other protuberance serving both as a contact and a detent. In practice I use a ball engaged in an aperture of a terminal strip that extends into the pocket. This provides one of the fixed contacts and the contactor has apertures or sockets to receive the ball in each of two or more positions of the contactor and handle.

In one such position the movable contactor engages another fixed contact, thereby bridging between the ball and such other contact. In another of said positions the contactor rests upon a dielectric portion of the casing, and the circuit between the fixed contacts is open.

In the drawing:

FIG. 1 is a plan view of an electric hair clipper appliance with a portion of the side wall of the cover portion of its casing broken away to expose the reciprocable handle slide and the fixed terminals of the switch.

FIG. 2 is a fragmentary plan view on an enlarged scale showing the terminals as they appear with the movable contactor and handle slide removed.

FIG. 3 is a fragmentary plan view similar to FIG. 2, but with the reciprocable contactor in place, the pin which connects it with the handle slide being shown in section.

FIG. 4 is a view taken in section on the line 4—4 of FIG. 3.

FIG. 5 is a view similar to FIG. 4 showing the contactor and handle in their open-circuit position.

FIG. 6 is a view taken in section on the line 6—6 of FIG. 4.

FIG. 7 is an exploded view showing in perspective the relatively separated parts of the switch, a portion of the clipper casing which is also a part of the switch being fragmentarily illustrated.

As already indicated the clipper is representative of many different types of appliances and the like in which the switch of the present invention may be incorporated. The clipper has a casing made of dielectric material and comprising a separable base 8 and cover 10. The margins 12 and 14 of the base and cover provide a guideway in which the handle slide 16 is reciprocable. Notches 18 and 20 in the ends of the handle slide are guided upon the margins 22 and 24 of the base which abut the guideway.

Immediately within the base section 8 of the casing are bosses 26 and 28 upon which the switch terminals 30 and 32 are mounted by means of screws 34 and 36. The respective terminals have wire retaining lugs 38 and 40 respectively to hold the electrical conductors leading thereto (not shown). An upward projection 42 of the boss 26 provides a shoulder at 44 abutted by the end 46 of the terminal 30, which end serves as a fixed contact. These parts are so located that when contactor 50 is reciprocated its contact portion 48 will ride from a closed circuit position (wherein it is engaged with the fixed contact portion 46 of terminal 30) to an open

circuit position (wherein it rests on the dielectric platform 42) and vice versa.

The moving contactor 50 has a hole at 52 engaged by a stud 54 mounted in the portion 56 of the handle slide 16 which overlies the switch contacts. As the handle slide is reciprocated manually in the guide slot of the casing, the movable contactor 50 reciprocates longitudinally.

The hole 52 in movable contactor 50 is intermediate its ends. Contact 48 is adjacent one end. Between the stud 54 and the other end are the holes or sockets 58 and 60 which alternatively receive a protuberance on terminal 32. In practice I use a ball contact 62 anchored simply by reason of its being in the aperture 64 of terminal 32. This ball rests in a pocket 66 of casing member 8, forwardly of the boss 28 to which the terminal 32 is anchored. Whatever the form of the protuberance it functions as a detent when the holes or sockets 58 or 60 engage it.

The collar 68 on stud 54 of handle 16 exerts downward pressure on the resilient contactor 50, causing its end to snap to and from engagement over the contact ball 62 whenever either of the apertures 58 or 60 is moved to or from registration with the ball. The engagement of the ball in either of the apertures or pockets 58 or 60 resists, with detent action, the reciprocation of the slide or handle 16 in a direction tending to disengage the contactor from the ball. When the disengagement has been completed the slide or handle will move freely until the other aperture of the contactor registers with the ball, whereupon the contactor will snap downwardly to embrace the ball. The ball contact and each respective socketed or apertured portion of the contactor defines the slide positions in which the circuit is respectively closed and open. The closed position is illustrated in FIG. 4, wherein the contactor 50 is shown bridging conductively between the contact ball 62 of terminal 32 and the contact portion 46 of terminal 30. The open position is shown in FIG. 5, which illustrates the aperture or socket 58 of contactor 50 engaged with the ball 62, the contact portion 48 of contactor 50 resting on the dielectric platform 42.

The switch disclosed is simple mechanically but very precise and positive in its operation.

While it happens that the casing illustrated is a part of the casing of the appliance per se, it will be noted that for the purposes of the present invention it is also the casing of the switch.

I claim:

1. A reciprocable switch having detents defining a plurality of positions, said switch comprising, in combination, first terminal means provided with a protuberance, second terminal means having a bearing surface, a movable contactor having contact portions for respectively cooperating with the protuberance and the bearing surface of said first and second terminal means, the contactor having spaced pockets selectively registerable with the protuberance in different positions of the contactor, and dielectric means providing a platform onto which a contact portion of the contactor rides from one of said terminals in approaching one of said positions.
2. In a sliding contactor switch, a strip contactor of elongated form having means for reciprocating it longitudinally and provided at one end with a first contact portion having spaced sockets and at its other end with a second contact portion, relatively fixed contacts in the path of reciprocation of said contactor and between which said contactor provides a bridging circuit in one of its positions of reciprocation,

one of said fixed contacts having a protuberance engageable in the respective sockets of the movable contactor in the open-circuit and the closed-circuit positions of the contactor, thereby providing detent action defining said positions, and
 a dielectric support adjacent the second fixed contact and engaged by the second contact portion of the contactor in the open-circuit position of the contactor.
 3. A switch according to claim 2 in which a terminal has an aperture, a ball in the aperture constituting the 10
 said protuberance.
 4. In combination,
 a casing provided with a guideway,
 a handle slide reciprocable in the guideway,
 a stud projecting from the handle slide,
 a movable contactor providing intermediate its ends 15
 with an aperture with which the stud is engaged for the movement of the contactor,
 the contactor having at opposite sides of the stud separate contact portions one of which is provided with 20
 sockets spaced longitudinally in the direction of slide reciprocation,
 a first fixed contact including a ball with which said sockets are selectively registerable in an open-circuit position and a closed-circuit position of said contactor,
 means for fixing the position of the ball against movement with the contactor and for making electrical connection thereto, and
 a second fixed contact to and from engagement with 25
 which the contactor is movable between its respective positions of detent engagement with the ball, said contactor establishing a bridging circuit between the ball and the second fixed contact in the circuit closing position of the contactor and being disengaged from the second fixed contact in the open-circuit position of the contactor.
 5. A switch comprising in combination,
 a casing having a side wall provided with a laterally

opening slot constituting a guideway and provided beneath said slot and internally of the side wall with boss means,
 a handle slide reciprocable along the guideway provided by said slot and having portions interlockingly engaged with the casing side wall in a tongue and groove relation,
 a flexible strip contactor connected with said slide within the casing side wall and elongated parallel to the side wall and having contact portions at opposite ends, its connection with said slide being intermediate said ends,
 relatively fixed contacts mounted on said boss means in the path of movement of said contactor,
 one contact portion of the contactor and one of said 15
 fixed contacts having complementary protuberances and socket means engageable in two different positions of the contactor to provide detent action defining said positions,
 the other end contact portion of the contactor being engaged with the other fixed contact in one of said positions and disengaged therefrom in another of said positions.
 6. A switch according to claim 5 in which the protuberance is a ball for which said one fixed contact has an opening in which the ball is disposed, the complementary socket comprising an aperture in which a portion of the ball is receivable and with which aperture said one contact portion of the movable contactor is provided.
 7. A switch according to claim 5 in which the boss means of said casing includes a platform adjacent the other fixed contact and positioned to receive and support said other end contact portion of the contactor when the contactor is in an open-circuit position.
